PRESSURE CASTING APPARATUS

Ellis J. Zickefoose, Chicago Heights, Ill., assignor to Griffin Wheel Company, Chicago, Ill., a corporation of Delaware

Application February 17, 1956, Serial No. 566,207

6 Claims. (Cl. 22—69)

This invention relates to apparatus for the pressure pouring of castings and particularly to apparatus comprising a permanent mold with a removable gate.

In the pressure casting of molten metal in a permanent mold, the metal is delivered under pressure from a ladle up through a pouring tube and thence through a gate into the casting cavity of the mold. After the casting cavity is filled with molten metal a plunger is activated to engage a seat adjacent to the inlet opening of the casting cavity and terminate further flow of the metal into the mold. Upon closure of such inlet opening, it is desirable that the molten metal drain from the pouring tube and return to the ladle. In order to assure the occurrence of return flow, provision should be made for the passage of gas into the interior of the pouring tube.

An object of the invention, therefore, is to permit the passage of gas into the interior of the pouring tube upon termination of the pressurized flow of molten metal into the casting cavity of a permanent mold.

Another object of the invention is to provide a porous gate member in a permanent mold that will permit the passage of gas through the walls thereof to the interior of the gate after closure of such gate to terminate metal flow therethrough.

Still another object of the invention is to provide a porous gasket between the mold and the pouring tube adjacent to the molten metal inlet of the mold, such gasket permitting the passage of gas therethrough to the interior of the tube after closure of the inlet by a stopper and thus breaking the vacuum lock existing in the pouring tube after termination of molten metal flow into the casting cavity.

Another object of the invention is to provide a gasket between the mold and the pouring tube to cushion and absorb the shock forces resulting from positioning a mold upon and in contact with the end of the pouring tube.

Another object of the invention is to provide a gate member in a mold, such member being renewable in situ by machining, and when excessively worn so that further renewal thereof is not practical, being readily removable and replaceable by a new gate member.

The invention embodies other novel features, details of construction and arrangement of parts which are hereinafter set forth in the specifications and claims and illustrated in the accompanying drawing, wherein:

Figure 1 is a central vertical sectional view of the apparatus according to the invention, and

Figure 2 is an enlarged view of a portion of the apparatus illustrated in Figure 1.

Referring now to the drawing for a better understanding of the invention, the pressure pouring apparatus is illustrated as comprising a cover 2 adapted to be detachably secured to a housing 4 to form therewith a sealed chamber 6, the housing being provided with an air conduit 7 leading to a suitable source of air under pressure. The housing is adapted to enclose a ladle 8 filled with

2

molten metal 10, such as steel, which is forced upwardly through a tubular pouring spout 12 into the cavity of a mold generally designated 14 responsive to an increase in air pressure within the housing. The mold 14 is preferably formed of a porous material such as graphite.

The pouring tube 12 is held by refractory cement 16 within a retainer cylinder 18. At the top of the pouring tube 12 a retainer ring 20 secured by screws 22 extending into retainer cylinder 18 forms an abutment for the refractory cement and gives additional strength to the composite construction. A wedge shaped ring 24 which enables the mold 14 to assume a tilted position is secured by Allen head screws 26 to the cover 2. A shoulder 28 is provided on the retainer cylinder 18, such shoulder being in mating engagement with a shoulder 30 formed on a male frustoconical ring 32 which is positioned to be adjacent to or engageable with a similar frustoconical member 34 of female construction. The member 34 has a shoulder 36 which receives and holds a plate 38. A recessed portion is formed on the inner periphery of the plate 38 and constitutes a leg 40 which is engageable with a similar leg 42 formed by recessing the outer periphery of a retainer ring 44. The two legs 40 and 42 are secured to each other by means of screws 46. As shown in the drawing, a gasket 48 is provided on top of the pouring tube 12. This gasket is in abutting relation with a removable gate member 50 when the mold is in position for a pour. The gate member 50 is removably received in a mold opening in the mold provided for that purpose and has a friction fit therein. It will be noted that the gate member 50 is provided with a peripheral ring 54 near the bottom thereof. The retainer ring 44 embraces or surrounds the gate member 50 and the peripheral ring 54 prevents the gate member from dropping out of the mold in the event that a tight friction fit between the member 50 and the mold is not obtained. Usually, however, a tight friction fit will be had due to contact of the member 50 with the mold at the upper and lower friction surfaces 57 and 55 of the member 50. The length of friction surfaces 55 and 57, which are separated by a relieved section 56, can be varied to suit, depending on the degree of friction required balanced against the ease of removability desired.

At its upper end member 50 is provided with a seat 58 which is engageable with a mating seat 62 on a stopper 60 which is movable to close the open end of the member 50 by downward actuation of a stem 64 attached to the stopper 60.

The removable gate member 50 is particularly adapted for use with a permanent mold formed of graphite blocks or other material, which mold can be renewed by machining when the casting cavity has been worn or eroded to an appreciable degree. It will be noted that the upper portion of the member 50 adjacent to the seat 58 has a longer friction surface 57 than that of lower friction surface 55. Such longer friction surface 57 permits machining of the mold with the gate member in place for a substantial number of renewing operations.

The removable gate member 50 is formed of a porous mixture, such as a clay-graphite composition. Of course, if the drag and cope blocks of the mold and the gate member are of a similar porous material, then sufficient passage of gas will be permitted through the mold blocks and through the gate member to break any vacuum lock existing in the pouring tube after the stopper has been moved into closed position, thus permitting the molten metal in tube 12 to return to the ladle. However, if the mold blocks should be made of a refractory material which is not porous such as copper, for example, then an air channel should be provided extending through one of the blocks of material and establishing

communication between the gate member and the atmosphere.

On the other hand, if it is desired to retain the advantages of a replaceable gate member but for one reason or another it is not desired to form same of a porous material, then the necessary gas leakage can be obtained solely from the use of a porous gasket 48. Such gasket may be of asbestos material which has sufficient porosity for the indicated purpose while at the same time offering a cushioning effect which will absorb some of the shock forces exerted upon the end of the pouring tube when a mold is positioned in place upon the top of same. It will thus be appreciated that either or both a porous gate member and a porous gasket can be used to break the vacuum lock existing in the pouring tube after termination of flow of metal into the casting cavity of the mold.

The gate member 50 is of one piece construction without vertical or horizontal lines of juncture and in this fashion cracking or chipping at lines of contact are eliminated to assure a relatively longer usable life of the gate members.

Figure 2 shows a space between the male and female frustoconical members 32 and 34 that is greatly exaggerated. In use, these members would be very close to contact with each other. If the members actually do establish contact it may be necessary to provide grooves in one or both of the contacting surfaces to permit air passage to the porous gasket in the event that a non-porous gate member is employed.

While the invention has been shown and described in connection with particular embodiments it is obvious to those skilled in the art that it is not so limited but it is susceptible to various changes and modifications without departing from the spirit and scope of the claimed invention.

I claim:

1. In a pressure casting apparatus of the type in which the molten metal in a housing is forced through a gate into the casting cavity of a permanent mold formed of porous material in response to an increase of fluid pressure in the housing, a housing cover having a pouring tube aperture, a pouring tube extending downwardly through said aperture for the upward passage of molten metal from the ladle to the mold cavity, a downwardly movable plunger having a seat engageable with a complementary seat on the gate, said gate being formed of porous material to permit the leakage of air through the mold and gate into the interior of the gate to break any vacuum existing in the gate and pouring tube and permit the metal in the pouring tube to return to the ladle after the plunger moves into sealing engagement with the gate.

2. In a pressure casting apparatus of the type in which molten metal in a covered housing is forced through a pouring tube and thence through a gate into the casting cavity of a permanent mold in response to an increase of fluid pressure in the housing, the combination of an annular cushioning member positioned between the gate and the pouring tube, said member being formed of a porous material which will readily permit the passage of air between the tube and gate into the interior of the gate.

3. In a pressure casting apparatus of a type in which molten metal in a housing is forced through a gate into the casting cavity of a permanent mold in response to an increase of fluid pressure in the housing, a housing cover having a pouring tube aperture, means to support the mold on the housing, a pouring tube extending downwardly through said aperture for the upward passage of molten metal from the ladle to the mold cavity, a movable plunger having a seat engageable with a complementary seat on the gate, a porous annular member positioned between the lower end of the gate and the upper end of the pouring tube, said annular member permitting the leakage of air into the interior of the pouring tube to break any vacuum existing therein and permit the metal in the pouring tube to return to the ladle after the plunger has moved into closure position, said supporting means including an opening to permit the passage of air from the atmosphere through the supporting means to said annular member.

20 4. In a pressure casting apparatus of the type in which molten metal in a covered housing is forced through a pouring tube and thence through a mold opening into the casting cavity of a permanent mold formed of porous material in response to an increase of fluid pressure in the housing, the combination of a removable tubular gate member formed of porous material and having a frictional fit in said mold opening, a movable plunger having a seat engageable with a complementary seat on the gate member, a porous annular member positioned between the 25 gate member and the pouring tube, said gate and annular members both permitting the leakage of air into the interior of the pouring tube to break any vacuum existing therein and permitting the metal in the pouring tube to drain back to the ladle after the plunger has moved into a 30 closure position.

35 5. A unitary, readily removable gate member for a permanent mold having an exterior mold cavity, comprising a generally cylindrical sleeve having a closure engaging seat at one end thereof adjacent said cavity, a peripheral frictional surface adjacent to said seat, a relieved peripheral portion adjacent to said friction surface, facilitating removal of said gate from said mold, a second friction surface adjacent to said relieved portion, a peripheral projection adjacent to said second friction surface and a 40 terminal portion engageable with a pouring tube.

45 6. A removable gate member according to claim 5, wherein the first peripheral friction surface is of greater length axially of the gate member than the length of the second friction surface to permit a surface of the mold cavity to be renewed by machining without removal of the gate from the mold.
